UNITED STATES PATENT OFFICE

ALBERT W. ENGEL, OF CHICAGO, ILLINOIS

CORNER-POCKET-MOUNTING DEVICE

Application filed June 2, 1928. Serial No. 282,469.

The purpose of this invention is to provide an improved device for securing photographs, pictures, cards and the like, to a suitable mounting, in a convenient and artistic manner, especially when the object to be mounted is provided with a substantial margin or border. It consists in certain features of construction as herein shown and described, and as indicated by the claims.

10 In the drawings:

Figure 1, is a plan view showing a picture provided with my improved corner mounting device, ready to be secured to a suitable mounting.

15 Figure 2 is a detail view of the device unattached, indicating in dotted lines, the manner of producing the same in quantities.

20 Figure 3 is a view of the reverse side of a portion of a picture with a corner pocket mounting applied thereto, the gummed areas being indicated by stippling.

In the drawings, 1, indicates a picture to be mounted, provided at its corners with the improved corner mounting devices, 2, which 25 are of a somewhat irregular outline, as shown in Figure 2. The mounting device is formed from a single piece of material such as cloth or paper and is gummed on one side for securing to a mount. An angular slit is provided in the mounting device, comprising two slit portions, 3, connected at their ends at approximately right angles with the apex on the longitudinal center line of the device. 30 The ends of the slit portions, 3, connect with terminal slit portions, 4, extending outwardly at right angles thereto. These terminal slit portions, 4, preferably, though not necessarily, are connected to the adjacent slits, 3, by curved portions, 5, so as to provide an attractive appearance as the slit forms the outline of the portion of the device that is visible on the face side of the picture when finally mounted. Flap portions, 6, for engaging the reverse side of the margin or edges of the object to be mounted, are formed by score lines, 7, extending from the center of the upper edge, 8, to the lateral edges, 9, parallel with the slits, 3, and communicating with the ends of the terminal slit portions, 4. These flaps are preferably cut to have edges, 10, ex-

tending parallel to the score lines, 7. The width of the flap may be approximately the same as the distance between the slits, 3, and the adjacent score lines, 7.

It will be understood that the portion of 55 the device other than the right angle area, 11, (bounded by slits, 3, 4 and score lines, 7), and the flaps, 6, may be of any suitable shape, but for simplicity and economy in fabrication, the outline of the lower edge of the remaining portion between the sides, 9, is of similar contour to that formed by the respective edges, 10, 8, 10. This outline provides projecting ears, 12, for securing the object to a mounting sheet or board. As indicated in 60 Figure 2, these corner mounting devices may be cut from a strip of material whose width is the desired width of the device determined by the distance between the lateral edges, 9. Further, this manner of forming the devices, 65 70 eliminates all waste and permits economical production.

When a picture or the like is to be mounted, the corner mounting device, 2, is moistened 75 on the gummed side, and the picture corner is inserted through the slits with the gummed side of the device opposite the face side of the picture, and with the adjacent lateral edges of the picture, aligning with the respective score lines, 7. The angular portion, 11, 80 bounded by slits, 3, 4 and score lines, 7, then being disposed over the face side of the picture, becomes adhesively secured thereto. The flaps, 6, which are bent on the score lines, 85 are folded back and secured partially to the reverse side of the picture and to some extent to the gummed side of the device. These flaps when folded back, form a pocket, and 90 thus insure proper seating on the corner of the picture or card when it is inserted through the slit. As the flaps, 6, are folded back, it will be seen that the two portions of former edge, 8, lie parallel to and adjacent each other. It is not essential that the corner pocket 95 mounting to be effective must have the angular portion, 11, adhesively secured to the face side of the object to be mounted, but, on the contrary, the flaps 6, may be first folded back, then the corner of the object inserted into the 100 slits, 3; then only the remaining gummed

surface needs be moistened for securing to a suitable mounting. This arrangement permits the removal of the picture or card from the mounting devices, when desired. Also, 5 it is to be noted that a pocket so constructed obviates tearing of the slits of the mounting device by constant insertion and extraction of the object.

I claim:—

10 1. A corner pocket of sheet material gummed on one side and having an angular slit with transverse terminal portions extending away from the enclosed angle of the slit, and having marginal areas doubled 15 over, toward the gummed surface by folding along lines respectively parallel to the main portions of the slit.

2. A picture mounting device comprising a fitting of sheet material gummed on one side 20 and having an area, a part of which is adapted to fit closely over the corner of a card or picture to be mounted with the gummed surface against the card, and having marginal portions folded to fit over the intersecting 25 edges of such card or picture adjacent its corner to engage its under surface, said area having a slit dividing it into the said part which fits over the corner of the card and another part which extends under the card 30 for adhesive securement to a mounting sheet.
